SPRING-BIASED PIVOTED CLOSURE

Fred V. Ettlinger, Jr., Port Richmond, N. Y.

Application June 13, 1947, Serial No. 754,547

2 Claims. (Cl. 220—35)

1

This invention relates to improvements in combined display boxes and packing containers having a hinged lid, and more particularly, to boxes which may serve the dual purpose of a container for merchandise, when closed, and as a display support for exhibiting the merchandise when the lid is open or partially open.

These containers or display boxes are used by manufacturers of candy, cosmetics, silverware, fountain pens, etc. for packaging either single items or sets. The manufacturer distributes same to retailers who in turn sell the complete package to the consumer.

These containers or boxes are also purchased empty by retailers and department stores from the box manufacturer. They in turn use them to box the article or set when a sale is made over the counter and also use them in show windows or on counters to display merchandise. Such as jewelry, stationary, wearing apparel, etc.

The general complaint among both retailers and manufacturers has been that they could not use a packaging container or gift box for display purposes without the use of an outside prop or support such as pins, etc. Accordingly, one object of the invention is to provide a box or container with the double feature and serving a dual purpose, adaptable for, either or both, display or packaging. Or in other words, a box or container normally used for packaging, but with an additional feature so that now it can be used for display purposes also.

In boxes of this type, it is desirable to vary the angle at which the lid is held open in order to display more advantageously the contents thereof due to lighting effects, angle from which the article is viewed, etc. The common practice heretofore has been to use pins, toothpicks or the like of various lengths as a prop or support interposed between the lid and the base in order to hold the lid open at the desired angle.

Likewise heretofore boxes of this nature have been provided with expensive and intricate clips coacting either with the hinge or with the lid and base to hold the box fully open or fully closed, but such clips are not designed to, and do not, hold the lid in any intermediate positions between fully open and fully closed.

Another object of this invention is to provide in a display box a hinged lid and which is held fully open, closed or in any intermediate position therebetween without the use of unsightly pins or props and without the use of an intricate or expensive clip.

Another object of this invention is to provide

5 a display box with a hinged lid that is held in any intermediate position between open and closed, which may be manufactured very economically and contains a minimum number of parts.

Other objects and advantages of this invention will become apparent as the description proceeds and is considered in connection with the accompanying claims and drawings wherein is 10 illustrated one embodiment of the invention, in which:

Fig. 1 is a perspective view of the display box embodied in this invention with the lid fully open so as to show the rigid tongue which holds the 15 lid in its intermediate open-closed position.

Fig. 2 is a top plan view of the display box embodied in this invention with the lid partially closed, showing the rigid tongue bearing against the chamber portion of the base.

Fig. 3 is a cross sectional view taken on the 20 lines 3—3 of Fig. 2, slightly enlarged to show the lid, hinge, holding device, and their coacting relation to each other.

Fig. 4 is a similar cross sectional view of the 25 box with the lid completely closed.

Referring now to the drawings wherein for 30 the purpose of illustration is shown a preferred embodiment of the invention, the numeral 5 designates a base or bottom section of a conventional display box. The bottom section 5 has a lid 6 hinged to the same, with a strip or collar 7 entirely surrounding the top portion thereof, and over which collar 7 the lower edges 8 of the lid 6 fit snugly when the box is closed. A hinge 9, shown as consisting of a strip of cloth, paper or other flexible material, and extending the length of both the lid 6 and the base 5 connects the lid to the base.

In the preferred embodiment of this invention 40 as illustrated, the box is of stiff paper, cardboard or the like, but it is to be understood that the box may be made in whole or in part of wood, metal, plastic, or other suitable material, without departing from the spirit of this invention.

The box may be lined with a sateen or other 45 ornamental or cushioning covering to more advantageously to set off the merchandise under display.

Affixed to the back or hinge edge 11, and intermediate the ends of the lid 6, is a rigid or substantially rigid tongue 12, which may be made of paper, plastic, composition material or metal as desired. The tongue 12 extends slightly below the lower edge of the back 11 of the box lid

6, in closed position, as best shown in Figs. 1 and 3, a sufficient distance so as to contact the outside face 13 of the back side of the collar 7 in a frictional or sliding cam action.

The tongue 12 may be glued or otherwise fastened onto the back 11 of the lid edge 6, as desired, depending upon the material used in the construction of the box.

The length which the tongue 12 may extend below the back 11 of the lid in closed position, is not necessarily critical but should be of sufficient length so as to engage firmly the surface 13 of the back of the collar 7, but should not extend sufficiently so as to cause undue distortion of the rear section of the base portion 5. From the foregoing, it will be seen that as the rigid tongue 12 is of the proper length and rigidity, it will bear against the outside back surface 13 of the collar 7 in such a frictional engagement as to hold gently but firmly the lid 6 in any position desired, intermediate, open or closed.

While I have shown and described the tongue 12 as being located approximately in the middle of the back edge 11 of the lid 6, and it is shown to be only a fraction of the length of the lid, it is to be understood that the tongue may be of any length desired and may be positioned at any place along the rear edge 11 of the lid where it will have the desired effective action. Furthermore, a plurality of these rigid tongues 12 could be affixed to the lid without departing from the spirit of this invention. The thickness of the tongue should be only sufficient to give it the rigidity desired.

While the bottom portion 5 of the box is shown as having a collar 7 therein, it is to be understood that the principle involved in my invention could be carried out equally as well if the collar 7 were removed and a yieldable insert were substituted for the back side 13 of the shoulder 7. The insert would be glued or otherwise fastened at the end or base to the bottom portion 5 of the box.

The operation of any invention can best be understood by referring to the drawings. In Fig. 1, I have shown the lid opened just a little wider than usual in order to clearly show the tongue 12. By comparing Fig. 1 with Fig. 3 it will be seen that the tongue 12 extends from the back edge 11 of the lid about the same distance that the collar 7 extends above the base section 5 of the box. When the lid 6 is opened, as shown in Fig. 1, the tongue 12 does not bear against the surface 13 of the collar 7. But if the lid is closed, as shown in Fig. 2, the tongue begins to bear against the surface 13 of the collar 7, and because the lid is hinged at 9, the tongue will move in an arc, thus having a cam action against the surface 13 causing the same to be distorted slightly, as shown more clearly in Fig. 3.

As the lid continues to be moved from an open to a closed position, the tongue 12, swinging in its arc, slides downward along the surface 13, distending this surface less and less as the lid closes until the lid is completely closed, as shown in Fig. 4. In this position, the tongue 12 extends downwardly into a space 14 provided between the shoulder 7 and the base 5 of the box. As will be seen from the above explanation, the friction of the tongue 12 against the surface 13 of the shoulder 7 is just sufficient to hold the lid in any desired position.

It is to be understood that other forms of boxes, materials, linings and the like may be used without departing from the spirit of the inven-

tion. Moreover, while the invention has been illustrated in one embodiment, modifications and changes may be made therein, except as specified in the claims.

I claim:

1. A combined packaging container and display box comprising a polygonal base member having a bottom with upstanding side walls including a back wall, a collar extending around the inside 10 of said side walls and protruding thereabove, said collar being securely affixed to some of the side walls and having a yieldable side adjacent the back wall, a lid member including a polygonal top having side walls therearound, a hinge attaching one of the side walls of said lid to the back side wall of the base member, said hinge being carried upon the lid adjacent the edge of the side wall and upon the bottom adjacent the edge of said back wall and positioned below the 15 top of said collar, a flat rigid tongue rigidly secured to and extending from the inside of the side wall of the lid adjacent the hinge, the extending edge of said tongue abutting in frictional engagement against the outside of the yieldable 20 side of the collar above the hinge and the back of said box when the lid is open and abutting in frictional engagement against the outside of the yieldable side of the collar between the back and said side adjacent said hinge when the lid is closed.

2. A combined packaging container and display box comprising a polygonal base member having a bottom with upstanding side walls including a back wall, a collar extending around the inside 30 of said side walls and protruding thereabove, said collar being securely affixed to all of the sides except that portion which is adjacent the back wall and which is free and unsecured, said portion of the collar adjacent the back wall being 35 anchored to the bottom of said box substantially throughout its length, said portion being yieldable with respect to the back wall, a lid member including a polygonal top having side walls therearound, a hinge attaching one of the side walls of said lid to the back side wall of the base member, said hinge being carried upon the lid adjacent the edge of the side wall and upon the bottom adjacent the edge of said back wall and positioned below the top of said collar, a flat 40 rigid tongue rigidly secured to and extending from the inside of the side wall of the lid adjacent the hinge, the extending edge of said tongue abutting in frictional engagement against the outside back of the yieldable portion of the collar above the hinge and the back of said box when 45 the lid is open and abutting in frictional engagement against the outside back of the yieldable portion of the collar between the back wall and said yieldable portion adjacent said hinge when the lid is closed.
